UNITED STATES PATENT OFFICE

101,541

DESIGN FOR A JOCKEY'S RACING BOOT

Adolph Michael Kroop, Laurel, Md., assignor of forty-nine per cent to Hilton A. Dabson, Miami, Fla.

Application June 16, 1936, Serial No. 63,331

Term of patent 3½ years

To all whom it may concern:

Be it known that I, Adolph Michael Kroop, a citizen of the United States, residing at Laurel, in the county of Prince Georges and State of Maryland, have invented a new, original, and ornamental Design for a Jockey's Racing Boot, of which the following is a specification, reference being had to the accompanying drawing, forming part thereof.

I claim:—

The ornamental design for a jockey's racing boot as shown.

ADOLPH MICHAEL KROOP.
